2 SHEETS—SHEET 2.

UNITED STATES PATENT OFFICE.

WILLIAM N. COX, OF MONTGOMERY, ALABAMA, ASSIGNOR TO THE
MOONEY DEVELOPMENT CO., A CORPORATION OF NEW JERSEY.

FURNACE DRAFT APPARATUS.

No. 823,396.

Specification of Letters Patent.

Patented June 12, 1906.

Application filed August 15, 1904. Serial No. 220,813.

To all whom it may concern:

Be it known that I, WILLIAM N. Cox, a citizen of the United States, residing at Montgomery, in the county of Montgomery and State of Alabama, have invented certain new and useful Improvements in Furnace Draft Apparatus, of which the following is a specification.

The present invention relates to improvements in furnaces, and more particularly to the type commonly known as "smoke-consuming," and the object in view is the provision of means for maintaining the highest attainable degree of perfection of combustion by the supplying of heated air at several and the most advantageous points relative to the location of the combustible matter.

The invention comprises, in combination with a fire-box and a hollow bridge-wall therefor, an air-supply pipe discharging into said bridge-wall, means for directing air from one end of said pipe into said bridge-wall, means for leading air from the said end of the pipe to the opposite end thereof and for directing air into said opposite end and thence into the bridge-wall, and means for supplying the air admitted to the bridge-wall to the products of combustion rising from said fire-box.

The invention comprises certain other novel constructions, arrangements, and combinations of parts, as will be hereinafter fully described and claimed.

In the accompanying drawings, Figure 1 represents a longitudinal vertical central section taken through a furnace embodying the features of the present invention, parts being illustrated in elevation. Fig. 2 represents a perspective view of a part of the heater and air-supply pipe illustrated as removed from the casing. Fig. 3 represents an enlarged detail, in front elevation, of a part of the header. Fig. 3^a represents an edge view of the same, parts being shown in section. Fig. 3^b represents a transverse vertical section taken on the plane of line 3^b-3^b of Fig. 3. Fig. 4 represents a longitudinal section taken on the plane of line 4-4 of Fig. 3. Fig. 5 represents a detailed fragmentary sectional view of the central portion of the air-supply pipe, illustrating the nozzle thereof.

Referring to the drawings by numerals, 1 indicates any suitable masonry-work or other casing for a boiler-furnace, the present invention being illustrated as applied to a

boiler-furnace, it being understood that the same is applicable to any type of furnace.

Mounted within the casing 1 is a boiler 2, supported in the usual manner at the sides and resting centrally upon a hollow bridge-wall 3. The hollow bridge-wall 3 divides the casing 1 beneath the boiler into a heat-chamber 4 in the rear and a fire-box 5 in the front, said fire-box being provided with the usual form of grate 6 or other devices found desirable. Extending transversely through the bridge-wall 3 at a point near the upper edge thereof are draft-eyes 7, communicating between the fire-box 5 and the heat-chamber 4, any preferred number of said draft-eyes being employed and each of the same being provided with series of apertures 8, communicating with the space between the sections of the hollow bridge-wall 3, so that air injected into said space will be free to move into the said draft-eyes and there to commingle with the products of combustion rising from the grate 6.

An air-supply pipe 9 extends from the rear of the casing 1 throughout the length thereof to the front of said casing, and said pipe is preferably disposed at one side of the casing and is provided intermediate its length with a discharge-nozzle 10, directed into the space between the sections of the hollow bridge-wall 3. The portion of pipe 9 extending past the fire-box 5 is of course positioned outside the fire-brick of said box, and therefore I have illustrated said portion of pipe 9 in dotted lines in Fig. 1. Here it is to be noted that a pipe 9 may be arranged at each side of the casing 1 instead of at one side, if desired. The air-supply pipe 9 is provided with a branch pipe 9', which extends from the pipe 9 at a point in the rear of the bridge-wall 3 and is led upwardly about the boiler 2, longitudinally of the same along the upper edge thereof, and downwardly in front of the boiler for purposes hereinafter mentioned.

At the front of the casing 1 is arranged a header, generally referred to by the numeral 11, said header comprising a relatively large tube 12, communicating with the front end of the supply-pipe 9' and arched over the usual furnace-doors 13, opening into the fire-box 5. Just in rear of the tube 12 is arranged a steam-pipe 14, which may be formed integral with the tube 12 and the web 15 interposed between said pipe and tube for divid-

ing the same. The steam-pipe 14 extends throughout the length of the arch formed by the tube 12, and at the end corresponding to the end of tube 12 communicating with pipe 9' said pipe 14 communicates with a steam-supply pipe 15', leading from the steam-dome 16' of the boiler 2. Leading from the tube 12 into the fire-box 5 are suitable discharge-nozzles 16 16, and discharging into each of said discharge-nozzles is an injector-nozzle 17, leading from the pipe 14 and extending across the tube 12 into the respective nozzle 16. A needle-valve 18 is preferably employed with each of the nozzles 17 for controlling the amount of steam flowing through said nozzle. The header 11 is thus made up of an arch formed of an air-supply tube and a steam-pipe with nozzles for permitting the injection of air by suction produced by the discharge of steam through such nozzles, and said header may be supplied with steam and air at one end only, as illustrated, or, if preferred, as above suggested, a pipe 9 may be arranged at each side of the casing 1, in which case air would be supplied to the tube 12 at each end of a pipe 9' leading from each of the pipes 9, and the pipe 14 might also be supplied with steam at each end. An even distribution of pressure could thus be very readily maintained, and, if desired, the header might be divided into two sections by a partition arranged centrally of the arch. Of course all of these features are within the scope and spirit of the present invention and may or may not be employed, as preferred.

A nozzle 19, similar in construction and arrangement to the nozzles 16, extends inwardly from tube 12 at the end communicating with the front end of the pipe 9' and projects longitudinally into the front end of the pipe 9, and a nozzle 20, similar to nozzles 17, is arranged for discharging steam into the nozzle 19, controlled by a suitable needle-valve 21, so that in operation when the valve 21 is opened steam passing through the nozzle 20 produces suction in the nozzle 19 and causes a discharge of air drawn through pipe 9 and branch pipe 9', the said discharge of air passing inwardly longitudinally of the pipe 9 until arriving at a point of the nozzle 10 of said pipe 9. At this point is arranged a baffle-plate 22, which extends transversely of the pipe 9 entirely across the same for a slight distance into the nozzle 10, so that air moving in through the pipe 9 under the pressure of steam discharged from nozzle 20 will be deflected and discharged out of nozzle 10, as indicated by the arrows in Fig. 5. This discharged air will of course produce a certain amount of draft within the rear portion of the pipe 9 and will cause such air within the said pipe as is not drawn through pipe 9' to move out through the nozzle 10, as indicated by the arrows in said Fig. 5.

For the purpose of effectively controlling 65 the precise amount of air discharged into the furnace I contemplate employing a valve at the rear end of the pipe 9 for controlling the amount of air entering said pipe. Said valve is seen in Fig. 1 of the drawings and consists 70 simply of a conical body 23, having its longitudinal axis in line with the longitudinal axis of the pipe 9. The valve-body 23 is preferably provided with eyes 25, surrounding guiding-bars 26 26, projecting rearwardly 75 from the end of the pipe 9. One or both of said eyes 25 may be provided with a set-screw 27, adapted to be tightened upon the respective bar 26 for locking the valve in the given position. The valve-body 23 may 80 thus be caused to enter the end of the pipe 9 and be locked in any desired position, even to the extent of being moved into contact with the end of the pipe for completely closing said end, or the valve-body may be moved rearwardly entirely outside of the pipe. 85

In operation the valves 17 and valve 21 may be set at any given position and the supply of steam to pipe 14 controlled in any preferred manner, or the valves 17 and valve 90 21 may be operated for controlling the discharge of steam, and when it is desired to supply heated air to the products of combustion within the fire-box and the heating-chamber it is only necessary when the valves 95 17 and valve 21 are open to admit steam to pipe 14, whereupon, assuming the valve 23 to be open, the discharge of steam through nozzles 16 will cause air to be drawn into the rear end of pipe 9, up through branch pipe 100 9' about the arched tube 12, and into the fire-box, and the discharge of steam through nozzle 19 will cause a similar intake of air and the discharge of same longitudinally rearward through the front portion of pipe 9 and out 105 of nozzle 10, the discharge through nozzle 10 effecting a draft in the pipe 9 past the branch pipe 9' and causing a certain amount of air within the pipe 9 to move out of nozzle 10 without having first been drawn up through 110 pipe 9'. The air discharged between the parts of the hollow bridge-wall 3 will find its way out through the apertures 8 into the several draft-eyes 7 and be consumed while aiding in the support of combustion. 115

The pipe 9' is passed about the boiler in the manner described for the purpose of further heating the air which is passed through pipe 9', and said pipe 9' may therefore be positioned in any desired manner within the casing 1 at the points most advantageous for subjecting same to the greatest number of heated units, whereby the atmosphere directed into the fire-box and supplied to the draft-eyes will possess a maximum temperature and will not have a chilling effect upon the products of combustion within the fire-box. 125

Having thus described my invention, what I claim as new, and desire to secure by Letters Patent of the United States, is—

1. In a draft apparatus, the combination with a furnace inclosure, of a pipe extending therethrough and provided with an opening intermediate its length for supplying air to the interior of said inclosure, a branch pipe between the air-inlet and the discharge-opening leading from said first-mentioned pipe, a nozzle in communication with said branch pipe and extending longitudinally of said first-mentioned pipe beyond the discharge-opening, a pressure-fluid injector discharging through said nozzle, and a baffle arranged in said first-mentioned pipe opposite the discharge-opening thereof.
2. In a draft apparatus, the combination with a furnace inclosure, of a pipe for supplying air to the interior thereof, having one end exposed to the atmosphere, a conical valve-body disposed with its longitudinal axis in line with the longitudinal axis of said pipe, eyes carried by said body, and guiding-rods supporting said eyes for maintaining said valve in various positions with respect to the exposed end of said pipe for controlling the amount of air entering the same.
3. In a furnace draft apparatus, the combination with a furnace inclosure, and a header arranged at the front thereof, of an air-supply pipe leading from the atmosphere through said inclosure to the header, and having an opening intermediate its length discharging into said inclosure, a branch pipe leading from the air-supply pipe at a point between the inlet and the discharge-opening and extending to and communicating with the header, nozzles leading from the header into said furnace inclosure, a nozzle leading from said header into the air-supply pipe, means for supplying a pressure fluid to said nozzles for producing a flow of air from the branch pipe through said nozzles, and means in said air-supply pipe for directing the air discharged through the nozzle extending into

said pipe through the discharge-opening therein.

4. In a furnace draft apparatus, the combination with a furnace inclosure, of an air-supply pipe extending into the same and formed with a discharge-opening intermediate its length, one end of said air-supply pipe being exposed to the atmosphere and the other being closed, a baffle arranged in said pipe opposite the discharge-opening, a branch pipe leading from the air-supply pipe at a point between the exposed end and the baffle and extending to a point for being heated and communicating with the said air-supply pipe at a point beyond the baffle, and means for creating a flow of air through said branch air-pipe and into said air-supply pipe for causing the air to be delivered against said baffle and to be directed thereby out the said discharge-opening.

5. In a furnace air-feeding mechanism, the combination with a furnace inclosure, of an air-supply pipe extending into said furnace from the rear thereof, the rear end of said pipe being exposed to the atmosphere, said pipe being provided with a discharge-opening intermediate its length for delivering air into the furnace inclosure, a baffle arranged within said air-supply pipe for preventing air from passing longitudinally of the pipe beyond the discharge-opening therein, and for directing air moving within said pipe through said opening, a branch pipe leading from said air-supply pipe at a point between said baffle and the open end of the pipe and extending to a point for being heated, and means for directing air under pressure from said branch pipe into that portion of the said air-supply pipe extending forwardly of the baffle.

In testimony whereof I affix my signature in presence of two witnesses.
